FRAME FOR TRANSITS AND SIMILAR INSTRUMENTS

Willard L. Egy, Charles I. Day, and Charles E. Smart, Troy, N. Y., assignors to W. & L. E. Gurley, Troy, N. Y., a Corporation of New York

Application August 31, 1931. Serial No. 560,514

9 Claims. (Cl. 33—46)

This invention relates to frames for transits and similar instruments.

The object of the invention is to produce a frame which may be simply constructed and one which is subject to the minimum distortion as the result of differential expansion of members of the frame.

The desired results are secured in a remarkable degree and are attributable in part at least to the symmetrical construction of the frame; to the fact that the frame members are essentially solids of revolution; and to the fact that the frame members are devoid of flanges and reentrant angles, and hence, are as nearly uniform in cross section as is practicable.

Another feature of importance to the final result is the fact that one of the two component parts of the frame is so connected to the other that it is stressed in hoop tension, and the other is subject to uniform radial compression. Hence, there are no internal stresses tending to induce distortion.

The ideal transit frame would be all in one piece and of homogeneous material, but the physical requirements for the metal forming the vertical spindle and the requirements imposed by available commercial methods for producing the rather complicated form of telescope standard, are not at present favorable to the use of a single material. Consequently, in practice, the use of a composite construction is desirable. One feature of the invention is the development of a composite structure in which separately formed component elements are permanently so connected as to be subjected to the minimum internal strains, and in which such internal strains as necessarily exist, are balanced, induce a stable condition, and, therefore, do not contribute to distortion.

As indicating the utility of the invention, it may be mentioned that it is well known that on a day when fast moving clouds periodically obscure the sun, a transit, if sighted on a distant target, will waver appreciably from the target, as the result of differential expansion of the frame. A transit having a frame constructed according to the disclosure of the present invention, does waver in a degree, but the amount is only a small fraction of that encountered with the best prior art instruments.

The invention will now be described in connection with the accompanying drawing, in which:

Fig. 1 is a perspective view of the complete frame.

Fig. 2 is a side elevation thereof.

Fig. 3 is a front elevation.

Fig. 4 is a plan.

Fig. 5 is a fragmentary radial section indicating the preferred composite construction.

Referring first to Figs. 1 to 4 inclusive, the vertical spindle on which the frame is mounted, is of familiar form, and is indicated generally by the numeral 10. The spindle 10 is provided with tapered bearing surfaces 11 and 12 and relief grooves 13 and 14. The bearing surfaces are intended to turn in the usual "quill" which carries the horizontal limb. The quill and horizontal limb are not features of the present invention and may follow established standards. Hence, they are not shown in the drawing. The shoulder 15, in the assembled transit, rests on the upper end of the quill, as usual, to limit the insertion of the spindle into the quill, and thus ensure a close but free-turning fit.

Supported on the upper end of the vertical spindle is the base plate, generally indicated at 16. This, in a unitary frame, would be in one piece, as indicated in Fig. 1. For ease of manufacture, the base plate is preferably composed of two parts, as indicated in Fig. 5. As shown in Fig. 5, there is a hub portion or head 16^a formed integrally with the spindle 10, and an annulus 16^b formed integrally with the telescope standards, herein-after described.

Preferably, the part 10, 16^a, is a drop forging and desirably, but not necessarily, may be composed of a "strong" aluminum alloy, heat treated and artificially aged. Suitable alloys and treatment are described in the patent to Archer and Jeffries, No. 1,472,739, granted October 30, 1923. The annulus 16^b and the standards may be variously formed and of various different materials, but a convenient method is casting, using an aluminum alloy. This may be for example an aluminum-copper alloy containing about 5% copper.

The parts 16^a and 16^b are threaded together, as indicated at 17, a shoulder 18 limiting the threaded engagement. In assembling the parts, the annulus 16^b is preferably heated somewhat and the hub 16^a is preferably chilled. The dimensional tolerances are close, so that when the parts are screwed together, they seize, and cannot be separated without destruction of one or both. The resultant frame has the essential characteristics of unitary construction, and can be successfully machined as a unit.

The annulus 16^b is stressed in hoop tension, so that it is in a balanced state of stress favorable to stability of form. The head 16^a is in a state of radial compression and, hence, stable.

The flange 19 is intended to carry verniers,

which are not features of the present invention, and, hence, are not illustrated.

The telescope standard structure is integral with the base plate 16, and in the composite construction shown in Fig. 5, is integral with the annulus 16^b.

The standard structure is substantially a solid of revolution with certain parts cut away to produce an open-work frame. It is concentric with the annulus and spindle 10 and with the base plate generally, a condition which minimizes any tendency to distortion.

The frame elements of the standard structure are a pair of diametrically opposed loop-shaped (generally elliptical) uprights 21 and intervening bowed interbraces 22. The loop-shaped uprights 21 have filleted bases 23 at the annulus 16^b, and the bowed interbraces 22 are connected at their ends with and merge into the uprights 21 and at their middles have filleted bases 24 connected with the annulus 16^b.

At the tops of the uprights 21 are bosses 25 which receive the telescope trunnion bearings generally indicated at 26. The construction of the bearings 26 is not a feature of the invention and any suitable bearing might be used to define the usual horizontal axis, i. e., an axis perpendicular to and intersecting the axis of the spindle 10.

The frame structure 21, 22 has a number of important characteristics. It is a solid of revolution with reference to the axis of spindle 10, i. e., the outer surface 27 is a surface of revolution about the axis of spindle 10, preferably a cone (as in the example illustrated), and the major (or lower) portion of the inner surface as indicated at 28 is also a similar surface of revolution about the same axis. The remaining surfaces 29, 31, 32 and 33 are, in the example illustrated, ruled surfaces whose generatrices are either parallel with the horizontal axis defined by bearing 26 or else perpendicular to such axis and to the axis of spindle 10. This is not important and may be departed from without affecting the character of the frame for strength and stability. The form is well adapted to profiling operations and has been found satisfactory.

The construction defined has advantages both from the standpoint of manufacture and from the more important standpoint of maintained accuracy and stability under varying conditions.

While a cast frame hand finished is sufficiently accurate in form for many uses, greater stability may be had by machining the standards to precise form and the frame is well adapted for machine finishing. In such case, the surfaces 27 and 28 are turned or ground on centers defining the axis of spindle 10. The remaining surfaces 29, 31, 32, and 33 are finished by profiling operations.

The transit frame structure is so designed that the elements 21 and 22 have, as nearly as practicable, uniform cross sectional areas, free from flanges and reentrant angles. Consequently they respond as nearly uniformly as is possible to temperature changes. In effect, therefore, the frame is so formed as to be subject to minimum thermal distortion, and to be capable of machining to precise dimensional standards, which materially enhance the result secured.

The composite construction is so contrived as to harmonize with the general principle of the invention. The annulus 16^b being a concentric unit with the standard structure and both being solids of revolution, the somewhat stressed condition of the annulus does not impart unbal-

anced stresses to the standards. The ideal condition is attained where all internal strains are relieved. This is possible in a unitary construction. In a composite construction the arrangement described minimizes the disturbing effect of such internal strains as exist, and the results secured in practice of the invention confirm the soundness of the principles underlying the construction.

While it is preferred that the surfaces 27 and 28 be cones (i. e., generated by right lines), they might within the broad scope of the invention be conoids. The surfaces 29, 31, 32, and 33 can be modified variously, but simple sections devoid of flanges, grooves, or reentrant angles are to be preferred.

Modifications are contemplated and the description given above should be interpreted as illustrative rather than limiting.

What is claimed is:

1. A frame for surveying instruments, comprising in combination a base plate member; a vertical spindle extending downward therefrom; and standards extending upward from the base plate member, the outer and a substantial portion of the inner surface of the standards being surfaces of revolution about the axis of said spindle.

2. A frame for surveying instruments of the type mounted upon a spindle having a vertical axis comprising in combination a base element and a standard structure integral therewith, said standard structure comprising substantially elliptical frame members connected with the base element, and arcuate brace members connecting the same with each other and with the base element, the outer and a substantial portion of the inner surface of said standard structure being surfaces of revolution about the spindle axis.

3. A surveying instrument frame of the type including a base plate, a vertical spindle, and standards, characterized in that the outer, and a substantial portion of the inner surface of the standards are surfaces of revolution about the axis of the spindle, and the standards are so formed in cross section as to be devoid of reentrant angles, and of substantially uniform cross sectional area.

4. A surveying instrument frame of the type including a base plate, a vertical spindle and standards, characterized in that the standards include looped bearing-supporting members connected with the base plate and integral arcuate braces also connected with the base plate, the outer and a substantial portion of the inner surface of the looped members and braces being surfaces of revolution about the spindle axis and so formed in cross section as to be devoid of reentrant angles and of substantially uniform cross-sectional area.

5. A frame element for surveying instruments comprising an annulus adapted to serve as the marginal portion of a base plate, and a standard structure formed integrally therewith, said standard structure comprising loop-shaped frame members connected with the annulus and arcuate brace members connecting the loop-shaped members with each other and with the annulus; the outer and a substantial portion of the inner surface of said standard structure being surfaces of revolution about an axis passing through the center of said annulus.

6. A transit frame comprising in combination a member including a vertical spindle and a
